CLAIM

The ornamental design for child chair, as shown and described.

DESCRIPTION

FIG. 1 is a top plan view of a child chair design;
FIG. 2 is a front elevation view of the child chair design of
FIG. 1;

FIG. 3 is a left side elevation view of the child chair design
of FIG. 1; and,

FIG. 4 is a top perspective view of the child chair design of
FIG. 1.

The broken line portion of the drawings is included to show
portions of the article that forms no part of the claimed
design.
